UNITED STATES PATENT OFFICE.

ALFRED KELLER, OF ST. CROIX, SWITZERLAND, ASSIGNOR TO GUSTAVE
ALFRED MERMOD, LEON MARCEL MERMOD, AND LOUIS PHILLIPE
MERMOD, OF ST. CROIX, SWITZERLAND.

FLUID-DISTRIBUTING APPARATUS.

No. 826,512.

Specification of Letters Patent.

Patented July 17, 1906.

Application filed August 5, 1905. Serial No. 272,804.

To all whom it may concern:

Be it known that I, ALFRED KELLER, a citizen of Switzerland, residing at St. Croix, canton of Vaud, Switzerland, have invented 5 certain new and useful Improvements in Fluid-Distributing Apparatus, of which the following is a full, clear, and exact description.

My invention relates to apparatus for the 10 distribution of fluid, and particularly liquid soap.

The object of the invention is to provide a simple and reliable construction for the manual control and distribution of fluids in quantities as desired.

The invention consists in improvements 15 the principles of which are illustrated in the accompanying single sheet of drawings.

Briefly described, it comprises a member 20 having a chamber with valve-control inlets and outlets and a plunger for forcing the desired amount of fluid from the chamber.

The details of mechanism for carrying out 25 my invention will be more clearly understood from the following specification.

Figure 1 is a front view of apparatus embodying the improvements of my invention, together with a fluid-reservoir. Fig. 2 is a 30 vertical section of the same. Fig. 3 is a plan view of the apparatus. Fig. 4 is a vertical section of the apparatus, taken on a plane at right angles to that shown in Fig. 2. Fig. 5 is a plan view of the base and valve mechanism. Fig. 6 is a vertical section of the same 35 on the plane of the line X X, Fig. 5.

1 indicates a reservoir of any suitable character, preferably of glass. Its location, construction, and method of attachment to the apparatus is immaterial.

2 is the body of the device constructed, 40 preferably, of metal.

3 is a suitable clamp or support for the apparatus.

4 is a feed-pipe for the fluid, leading from 45 the top to the bottom.

5 is a base member, preferably removably attached to the body and having a U-shaped passage 6. One end of this passage receives the lower end of the feed-pipe 4 and the other 50 end leads to the chamber 7.

8 is a ball acting as a valve to prevent fluid

from passing from the chamber 7 back through the passage 6.

8' is a plate removably secured to the base 5, having a finger which prevents the ball 8 55 from rising too far from its seat.

9 is a passage similar to the passage 6, which leads from the chamber 7 and has its outlet beneath the plate 8'.

10 is a ball normally seated in the outlet 60 of the passage 9 by means of the spring 11.

12 is the outlet.

13 is a piston or plunger located in the body 2 above the chamber 7.

14 is a cap secured to the plunger 13, and 65 15 is a spring, which engages the under side of the cap 14 and normally presses the plunger upward.

16 is a stop-piece, which prevents the plunger from rising above its proper position.

17 is the head of the plunger, formed of suitable material for packing the joint and preventing the escape of fluid upward around the plunger.

18 is a manually-controllable lever, which 75 passes through an opening in the plunger 13 and is pivoted to the body 2 by means of the screw 19.

Normally the parts are in the position shown in Fig. 2. When the lever 18 is 80 pressed downward, the plunger 13 descends, and any fluid within the chamber 7 is forced through the passage 9 and outlet 12, the valve 8 being closed and the valve 10 being opened by the pressure. When the lever 18 85 is released or moved upward, fluid from the reservoir flows through the conduit 4 and passage 6 to the chamber 7, the valve 8 opening. The pressure of the spring 11 is sufficient to normally hold back whatever fluid 90 is within the chamber 7. The same amount of fluid is delivered every time the lever 18 is depressed its full extent. Varying amounts of fluid may be delivered by varying the extent of depression of the lever 18.

The parts are all constructed so that they 95 may be readily cleaned.

All joints through which the fluid might escape are properly packed.

The device may be made in any size and 100 suitable for delivering any quantity or kind of fluid; but the mechanism herein illustrated

is particularly adapted for the delivery of liquid soap.

The advantages of the apparatus will be apparent to those who are skilled in the art.

5. What I claim is—

1. In a fluid-delivery apparatus, the combination of a body having a feed-conduit and a pressure-chamber, a controllable plunger in said chamber, a base member having an upwardly-turned supply-passage at the foot of said feed-conduit, the upwardly-turned end leading into said pressure-chamber, a U-shaped discharge-passage, a valve for each of said passages, and a seat in each passage for the valve therein, said seat being below said valve in each instance.

2. A device for the delivery of fluids having a feed-conduit, a retaining-chamber, a passage connecting said feed-conduit and said chamber, a valve for said passage preventing the flow of fluid back from said chamber, a seat for said valve, said seat being below said valve, an outlet-passage leading from said chamber, a valve therefor normally preventing the flow of fluid, and controllable means for increasing the pressure in

said chamber and forcing fluid out therefrom, a detachable base member, both of said valves being carried thereby.

3. In a fluid-delivery apparatus, a body having a chamber, a plunger therein, a base member having passages leading to and from said chamber, a valve in the inlet-passage, a valve in the outlet-passage, and a removable plate for holding said valves in position.

4. In a fluid-delivery apparatus, a body having a chamber, a plunger therein, a removable base member having U-shaped inlet and outlet passages, a gravity-valve for said inlet-passage and a spring-pressed valve for said outlet-passage.

5. In a fluid-distributing apparatus, a body having a chamber, a plunger therein, a removable base member having U-shaped inlet and outlet passages, a valve in each of said passages to control the same, and a seat for each valve, respectively, each of said seats being below the respective valves.

ALFRED KELLER.
